UNITED STATES PATENT OFFICE.

CHARLES S. ASH, OF GENEVA, NEW YORK.

WHEEL-HUB.

1,316,997.

Specification of Letters Patent. Patented Sept. 23, 1919.

Application filed August 10, 1918. Serial No. 249,278.

To all whom it may concern:

Be it known that I, CHARLES S. ASH, a citizen of the United States, residing at Geneva, in the county of Ontario and State 5 of New York, have invented certain new and useful Improvements in Wheel-Hubs, of which the following is a full, clear, and exact description, such as will enable others skilled in the art to which it appertains to 10 make and use the same.

This invention relates to quick-detachable vehicle wheels of the type wherein an outer hub, structurally associated with the tire-carrying rim by spokes or otherwise, is 15 adapted to fit removably over an inner hub arranged on the vehicle axle, and interlocking parts are provided to effect transmission of the driving and braking forces through the inner hub to the wheel.

20 The invention is more particularly directed to an improved construction of the two hubs and their rotary interlocking connection whereby removal of the wheel is facilitated and wear or mutilation of the rotary 25 interlocking parts in service is substantially eliminated.

A further object is to provide a wheel construction of the character mentioned having functional advantage, manufacturing economy and structural superiority.

30 Other objects and advantages will be in part noted hereinafter in connection with the following description of the accompanying drawings, which illustrate typical embodiments of the invention, and in which—

Figure 1 is an end elevational view of an outer hub mounted on an inner hub;

Fig. 2 is a partial central sectional view through the hubs;

40 Fig. 3 is a transverse sectional view on the plane of line 3—3 of Fig. 2;

Fig. 4 is a detail sectional view of a modified form of driving lug; and

Fig. 5 is a partial central sectional view 45 through inner and outer hubs embodying a modified form of the invention.

Referring more particularly to the drawings, there is shown a sheet metal outer hub 1 connected, by spokes 2 or otherwise, with 50 a tire-carrying rim (not shown) and adapted to fit removably over an inner hub 3 arranged for mounting on the vehicle axle and fixedly associated with the latter by suitable means. In the case of the driving wheel the inner hub 3 is adapted to transmit the driving and braking forces by means of complementary projections 5 on the inner hub

received in recessed sockets 6 in the outer hub whereby a relative rotary lock is insured when the parts are assembled.

60

Heretofore it has been common to support the inner end of the outer hub on the inner hub by circumferentially continuous contacting surfaces, whereby alinement of the hubs is insured, while the driving and braking forces are transmitted by axial driving lugs on the inner hub radially spaced from said contacting surfaces and received in complementary apertures in the outer hub. By the present invention the projections 5 70 on the inner hub function both to transmit the driving and braking forces and to support the inner end of the outer hub in alinement and at circumferentially spaced points of limited area only. Referring to Fig. 2, 75

the inner hub wall is provided with a plurality, in this instance three, of integrally offset projections 5 extending radially and axially beyond the planes of the adjacent metal, and the outer hub is provided with a 80 similar number of integrally recessed sockets 6 opening radially and axially to receive projections 5. The outer hub is otherwise spaced from and out of contact with the inner hub. The non-symmetrical inter-engaging surfaces of the two hubs, when assembled, consequently effect alinement there- 85

of, establish a rotary lock, and furthermore afford a radial support for the outer hub, at its inner end, at points symmetrically arranged about the axis and circumferentially spaced intervals. As a result of the last-mentioned action the two hubs are always capable of easy separation, since freezing therebetween over the contact surfaces is 95 minimized and practically eliminated. At the same time the interlocking convexities 5 and concavities 6 being integrally formed in the hubs by drawing or otherwise, facilitates and cheapens the manufacture of the hubs 100 and reduces the number of parts.

Save at the points mentioned, the outer hub 1 is spaced from the inner hub 3 (Fig. 2), and the improved cap nut 7 is employed to hold the hubs axially assembled and assist in maintaining their permanent alinement. For this purpose the inner hub is externally threaded at 8 adjacent its outer end to receive the internal threads of the cap nut when positioned. The latter is further provided with a reverse overhanging portion 9 having a beveled or inclined surface 10 adapted to contact with and wedge against a correspondingly inclined external surface 110

11 at the extremity of the outer hub 1. The operation of these parts will be apparent. That is, as nut 7 is screwed home on the inner hub, surfaces 10 and 11 contact and 5 wedge together to effectively lock the nut against loosening and also to align and reinforce the outer end of the outer hub in correct assembly.

In the modification shown in Fig. 4 the 10 integrally recessed sockets 6 of the outer hub remain as before. Rigid complementary driving pins 5' are employed on the inner hub to seat therein for establishing the rotarv lock and supporting the outer hub.

15 A further modification, illustrated in Fig. 5, embodies integral concavities 6' on the outer hub which are radially spaced farther from the axis and open in an axial direction only to receive the tapered ends 12 of complementry rigid driving lugs 5'' disposed at corresponding intervals on the inner hub. 20 3. In this construction, as in the others, however, the contacting bearing surfaces of the driving lugs 5'' and sockets 6' constitute 25 the support for the outer hub and establish its alinement. By reason, likewise of the end taper 12 of the driving lugs and the complementry inclined walls of the socket 6', self alinement and uniform wear is insured. 30 That is to say, provision is made whereby the outer hub is always movable inwardly to an alined limit when the cap nut 7 is threaded home.

Having described my invention, what I 35 claim as new and desire to secure by Letters Patent is:

1. In a wheel of the character described, in combination, an inner hub having a plurality of rigid projections disposed symmetrically about its axis, and an outer hub fitting removably upon said inner hub and having its wall indented to provide interior recesses opening radially and axially to receive and bear on said projections only 45 whereby said hubs are alined in assembly, are locked against rotation, and the outer hub is supported at circumferentially spaced points only on said inner hub.

2. In a wheel of the character described, 50 in combination, an inner hub having a plurality of rigid integral projections, disposed symmetrically about its axis and having curved outer bearing surfaces, and a sheet metal outer hub fitting removably over said inner hub and having imperforate concavities complementary to said projections for receiving the latter, whereby said hubs are alined in assembly and locked against relative rotation, said outer hub being supported 55 on said projections and otherwise spaced from said inner hub, and said elements being constructed and arranged so that the areas of the bearing surfaces are materially

less than the circumferentially adjacent spaced areas.

65

3. In a wheel of the character described, in combination, an inner hub having a plurality of driving convexities disposed about its axis, and an outer hub removably fitting over said inner hub and having a plurality 70 of complementary concavities to receive and bear on said convexities, whereby said hubs when assembled are locked against relative rotation, the inside of said outer hub being otherwise spaced from and unsupported by 75 said inner hub.

4. In a wheel of the character described, in combination, an inner hub having a plurality of rigid driving projections disposed about its axis, a sheet metal outer hub removably fitting over said inner hub and having a plurality of complementary sockets to receive and bear upon said projections, whereby said hubs when assembled are locked against relative rotation, said outer hub 80 being otherwise spaced from said inner hub, and a cap nut threaded on the outer end of one of said hubs and contacting with the outer end of the other for maintaining the same in alinement and holding it against 85 axial displacement.

90

5. In a wheel of the character described, in combination, an inner hub having a plurality of rigid driving projections disposed about its axis, an outer hub removably fitting over said inner hub and having complementary recesses to receive said projections for locking said hubs when assembled against relative rotation, said outer hub being otherwise spaced from said inner hub 100 and having an externally inclined surface at its outer end, and a cap nut threaded externally on the outer end of said inner hub and having an inclined portion to bear against the inclined portion of said outer 105 hub for retaining said hubs against axial displacement and maintaining the outer ends thereof in alinement.

95

6. In a quick detachable wheel, in combination, an inner hub, an outer hub adapted for spoke and rim attachment telescoping thereon, said hubs having interfitting parts adjacent their inner ends affording load-supporting bearings and the remaining interior of said outer hub being spaced from 115 and unsupported by said inner hub, and a securing nut screwing on said inner hub and having only an overhanging portion contacting with the exterior surface of said outer hub at its outer end to aline said hubs.

120

In testimony whereof I affix my signature, in the presence of two witnesses.

CHARLES S. ASH.
